TOWEL DISPENSER

Stanley J. Bye, Neenah, Wis., assignor to Kimberly-Clark Corporation, Neenah, Wis., a corporation of Delaware

Filed Feb. 25, 1969, Ser. No. 15,894

Term of patent 14 years

Int. Cl. D9—04

U.S. Cl. D52—2

FIG. 1.

FIG. 2.

FIG. 3.

I claim:

The ornamental design for a towel dispenser, substantially as shown and described.
